UNITED STATES PATENT OFFICE.

EDWARD E. PINKERTON, OF CHICAGO, ILLINOIS.

DESIGN FOR AN ENVELOP.

SPECIFICATION forming part of Design No. 33,242, dated September 25, 1900.

Application filed August 24, 1900. Serial No. 27,957. Term of patent 14 years.

To all whom it may concern:

Be it known that I, EDWARD E. PINKERTON, a citizen of the United States, residing in the city of Chicago, county of Cook, and State of Illinois, have invented and produced an original Design for Envelops, of which the following is a specification, reference being had to the accompanying drawings, forming part thereof.

o In said drawings, Figure 1 is an obverse view of an envelop embodying my novel design. Fig. 2 is a reverse view of the envelop.

An envelop embodying my novel design is made generally rectangular in form. The reverse wall of the envelop extends some distance beyond the obverse wall thereof, and the extended part or flap of said wall has the general form of a triangle joined at its base to the reverse wall in the region of the free margin of the obverse wall of the envelop. The flap or extended part of the reverse wall is not truly triangular, but is widened at its apex to form on the sides thereof at said apex laterally-projecting knobs. The outer or apex end of said flap is provided between said laterally-projecting knobs with an inwardly-directed slit, which extends beyond the narrowest portion of the flap, thereby dividing the outer end of said flap into two laterally-separated tongues. The extreme margins of said tongues are curved, while the lateral margins thereof

approach a straight line and extend obliquely inwardly to the narrowest part of the flap, where they intersect, the generally-straight line constituting the oblique lateral margin 35 of the inner part of the flap.

The obverse wall of the envelop is provided at a distance inside of the free margin thereof with a slit of less length than the width of the envelop and which slit is disposed parallel with the free margin of said wall.

The principal or characteristic features of an envelop embodying my novel design are embraced in the generally-triangular extension or flap connected with the obverse wall 45 of the envelop, said flap having at its outer end laterally-directed knobs and being provided between said knobs with an inwardly-directed slit forming two lateral tongues at the end of said slit and the slit in the obverse 50 wall, which is disposed parallel to the free margin of said wall.

I claim as my design—

The design for an envelop, substantially as herein shown and described.

Signed at Chicago, Illinois, this 21st day of August, 1900.

EDWARD E. PINKERTON.

In presence of—

WILLIAM H. HALL,

CARL H. CRAWFORD.
